UNITED STATES PATENT OFFICE.

ARTHUR F. DRAPER, OF DETROIT, MICHIGAN, ASSIGNOR TO CHRYSLER CORPORATION, OF DETROIT, MICHIGAN, A CORPORATION OF DELAWARE.

DESIGN FOR AN AUTOMOBILE INSTRUMENT PANEL.

Application filed April 1, 1927. Serial No. 21,425. Term of patent 14 years.

To all whom it may concern:

Be it known that I, ARTHUR F. DRAPER, a citizen of the United States, residing in the city of Detroit, county of Wayne, and State of Michigan, have invented a new, original, and ornamental Design for an Automobile Instrument Panel, of which the following is a specification, reference being had to the

accompanying drawing, forming a part thereof, in which the figure is a front elevation view showing my new design.

What I claim is:

The ornamental design for an automobile instrument panel, as shown.

ARTHUR F. DRAPER.
